CLAIM

The ornamental design of a portable DVD player with external battery, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a portable DVD player with external battery according to the new design (in closed position);

FIG. 2 is a top plan view thereof;

FIG. 3 is a front elevation view thereof;

FIG. 4 is a right side elevation view thereof;

FIG. 5 is a left side elevation view thereof;

FIG. 6 is a back elevation view thereof;

FIG. 7 is a bottom plan view thereof;

FIG. 8 is a perspective view thereof (in open position); and,

FIG. 9 is a perspective view thereof (with screen swiveled).

Portions in broken lines are for illustrative purposes only and form no part of the claimed design.
